[57] CLAIM

The ornamental design for a flexible barricade marker, as shown and described.

DESCRIPTION

FIG. 1 depicts a perspective view of a flexible barricade marker showing my new design;

FIG. 2 depicts a front plan view thereof;

FIG. 3 is a side elevational view thereof, with the opposite side being a mirror image;

FIG. 4 depicts a top plan view thereof;

FIG. 5 depicts a bottom plan view thereof;

FIG. 6 is a rear elevational view of a second embodiment thereof, wherein the only difference resides in the omission of a reflector on one side; and,

FIG. 7 is a side elevational view thereof, with the opposite side being a mirror image.
